UNITED STATES PATENT OFFICE.

GEORGE I. ROCKWOOD, OF WORCESTER, MASSACHUSETTS.

ALARM-CONTROLLING DEVICE FOR SPRINKLER SYSTEMS AND THE LIKE.

Application filed March 4, 1922. Serial No. 541,229.

To all whom it may concern:

Be it known that I, GEORGE I. Rockwood, a citizen of the United States, residing at Worcester, in the county of Worcester and 5 State of Massachusetts, have invented a new and useful Alarm-Controlling Device for Sprinkler Systems and the like, of which the following is a specification.

This invention relates to the operation 10 of an alarm to show the opening of one or more sprinklers of an automatic fire extinguishing sprinkler system or other analogous installation. Numerous inventions have been made in this line but those in 15 use are open to the objection that in case of the closing of the alarm valve on account of a reversal of flow of the water, the supply to the alarm device may be interrupted. This sometimes stops the alarm 20 and sometimes operates it intermittently.

The principal object of this invention is to provide means whereby, after the alarm is once started, it will be operated continuously until it is shut off by hand; and 25 to provide this in a simple form that cannot get out of order under ordinary circumstances, and that will not fail to work. Further objects and advantages of the invention will appear hereinafter.

Reference is to be had to the accompanying drawing which is a sectional view of the alarm check valve of a sprinkler system with a preferred embodiment of this invention applied thereto.

Although capable of general use, the invention is shown as applied to an alarm valve comprising a chamber 1 having an inlet passage 2 connected with a supply pipe. This chamber is provided with the 40 usual valve which may be raised to permit the passage of water through the passage 2 into the chamber 1 and out through the stand pipe 3 to the sprinkler system whenever the pressure of water on the under- 45 side of the check valve exceeds the pressure on the upper side. It is understood of course that while the sprinkler heads of the system are closed, and in the absence of water hammer, no movement of 50 water into the chamber 1 takes place; but when a sprinkler has opened the water passes through the chamber 1 in an uninterrupted manner provided nothing causes

a momentary cessation or reversal of flow of the water in pipe 3. 55

It is usual to connect this alarm valve chamber with devices which will sound an alarm or display a signal whenever the valve 5 is raised long enough for water to get to them, and I have shown a usual 60 construction in the form of annular passage or perforation 6 opening under the valve 5. The water is conducted from this passage through a pipe 7 in one way or another to a pipe 8 and from that to an 65 alarm device 9. I have shown here a particular alarm which is shown in my Patent No. 1,114,528. This is for the purpose of illustration only, as any desired kind 70 of alarm or signal can be employed.

It will be understood that whenever the check valve 5 closes again after once opening, the flow of water to the alarm will cease. This closure sometimes occurs after the alarm has started and operated perhaps only for 75 an instant. When it does occur, the fact that valve 5 is a differential valve and the further fact that considerable air is always compressed within the pipe system explain why it takes a certain appreciable time for 80 the escape of water through the open sprinkler to reduce the pressure in pipe 3 sufficiently to cause valve 5 to reopen. This phenomenon sometimes causes an intermittent 85 alarm which is considered objectionable. Experience shows it is more likely to happen when but one head has opened than when several heads are discharging.

To avoid this difficulty I provide a casing 90 into which the pipe 7 has a free passage. The chamber 10 delivers water directly to the pipe 8. In this casing I place a diaphragm 11 operated by spring 12 to force it into the position illustrated. This diaphragm has a central stud or connection 13 95 which is provided with a valve 14 that closes a passage in a valve seat 15 normally. This passage is connected with a pipe 16 having a valve 17 and opening into the stand-pipe 3. The valve 17 is kept open so that 100 the valve 17 alone prevents the entrance of water into the casing from the stand pipe. Normally the spring 12 holds the valve 14 closed.

In the chamber 10 is a drain valve open- 105 ing in a seat 20 which seat has an arm 21

on which is pivoted a valve lever 22 having a valve 23 for closing the opening at 20. This lever has a forked arm which engages a pair of projections 24 on the stud 18 or 5 otherwise connected with the diaphragm to move it. This valve opening 20 is a mere drain opening and is made of such a size that the water supplied through the pipe 7 will rise in the chamber 10 in spite of this 10 open drain.

In the operation of the device, when the valve 5 opens water will rush through the normally open "stop and waste" valve 26 and through the pipe 7 into the chamber 10. After it fills this chamber its pressure, 15 added to that acting against the valve 14, will force the diaphragm 11 over to the left against the reaction of the spring as soon as the hydrostatic pressure due to the water 20 mounting in pipe 8 is sufficient to overcome the spring; and the diaphragm may be designed large enough to cause the valve 14 to open even before the water reaches the alarm. This results in swinging the lever 25 22 over to the left and closing the valve 23.

As the movement of the diaphragm 11 will take the valve 14 with it, and as the stop valve 17 is normally open, water will then flow into the chamber 10 through the pipe 30 16 independently of pipe 7 and there will be thus two sources of supply to this chamber. This not only adds to the water pressure at the alarm but another advantage of this construction is that even if, for any 35 reason the valve 5 drops back to its seat and the water is cut off from the pipe 7, after having once operated the alarm, that will have no effect on the continuousness of the flow of water to the alarm device for, whatever happens to the valve 5, the water will 40 continue to hold back the spring 12 and thus keep the valve 14 open and cause the alarm to be sounded positively and without any danger of subsequent interruption by reason 45 of closure of valve 5.

After the fire is out and the heads which have opened have been replaced with new ones and the system has been refilled with water and is under pressure from the source 50 of the water supply, the attendant may restore things to normal condition by closing the valves 17 and 26. The water in the drip chamber will then drain out through the waste outlet of the valve 26. When the 55 water gets low enough the spring 12 will move the diaphragm back to the position shown and close the valve 14. Then after the valves 26 and 17 are both reopened by hand, the device is ready for operation again 60 the next time a sprinkler head opens.

Although I have illustrated and described the invention as applied only to a single type of riser and alarm I am aware of the fact that it is capable of general application 65 and also that variations can be made in the

details of construction and arrangement of parts without departing from the scope of the invention as expressed in the claims. Therefore I do not wish to be limited in these respects, but what I do claim is:—

1. In a system of the class described, the combination with a supply pipe, a distributing pipe, a check valve for admitting water from said supply pipe to said distributing pipe, a valve seat for said valve, said seat having an opening therein, and means communicating with said opening and adapted to deliver water to an alarm or signal device to operate the same, of a valve adapted to be controlled by the water discharged through said communicating means for admitting water to the alarm or signal device directly from the distributing pipe.

2. In a sprinkler system, the combination with a check valve, a connection from the seat of the check valve, and a chamber into which said connection discharges, of means for connecting said chamber with an alarm or signal, which will cause it to operate upon the filling of the chamber with water under pressure, a connection with said chamber from the distributing pipe of the sprinkler system independent of the check valve and the first named connection, a spring, a diaphragm in the chamber held in position by the spring, and a valve operated by said diaphragm and normally held closed for controlling the admission of water to the chamber from said connection, whereby upon the filling of the chamber with water under pressure the diaphragm will move against its spring and open the valve and admit another current of water into the chamber from the distributing pipe of the system.

3. In a sprinkler system, the combination with a connection from the seat of the alarm check valve of said system, and a chamber into which said connection discharges, of an alarm device connected with said chamber to be operated by water passing through it, a pipe connected with said chamber from the system side of the check valve, a spring-pressed diaphragm in the chamber, a valve operated by said diaphragm and normally held closed for controlling the admission of water thereto through the connection with the last named pipe, and a lever in the chamber connected with the diaphragm to operate thereby and having a valve thereon, said chamber having a drain opening, and a valve seat for said drain opening located in such position that the last named valve will close it when the diaphragm moves back against the spring pressure.

4. In a sprinkler system, the combination with a chamber, a pipe connected with said chamber from the low pressure side of the sprinkler system, a spring-pressed dia-

phragm in the chamber, a valve operated by said diaphragm and normally held closed for controlling the admission of water thereto, and a lever in the chamber connected with the diaphragm to be operated thereby and having a valve thereon, said chamber having a drain opening and a valve

seat for said drain opening located in such position that the last named valve will close it when the diaphragm moves back against the spring pressure. 10

In testimony whereof I have hereunto affixed my signature.

GEORGE I. ROCKWOOD.
